C. M. SEARL

LAST

Original Filed April 21, 1924

INVENTOR.

By Clinton M. Searl,
Paulin & Paulin
ATTORNEYS.

UNITED STATES PATENT OFFICE.

CLINTON M. SEARL, OF PORTSMOUTH, OHIO, ASSIGNOR TO THE VULCAN LAST COMPANY, OF PORTSMOUTH, OHIO, A CORPORATION OF OHIO.

LAST.

Original application filed April 21, 1924, Serial No. 707,796. Divided and this application filed November 24, 1924. Serial No. 751,760.

To all whom it may concern:

Be it known that I, CLINTON M. SEARL, a citizen of the United States, residing at Portsmouth, in the county of Scioto and 5 State of Ohio, have invented certain new and useful Improvements in Lasts, of which the following is a specification, reference being had therein to the accompanying drawing.

10 My invention relates to an improvement in lasts, and is particularly directed to lasts of the divided type—that is to say, to that type of last which is divided into two parts, a toe part and a heel part, movable relatively to each other to collapsed and extended positions. The present application is a 15 division of my application filed April 21, 1924, Serial No. 707,796.

It is desirable in lasts of this type that the 20 last be capable of being easily collapsed so that it may be removed from a shoe without injury to the lining of the shoe and without stretching the shoe out of place.

In lasting a shoe the last is held upside down—that is, with the sole side uppermost—and inasmuch as a great deal of pressure is put on the toe of the last during the lasting operation, this tends to collapse the last, and consequently one of the 25 objects of my invention is the provision of a construction in which the last is capable of withstanding the stresses to which it is subjected during the lasting operation without collapsing, but may be readily collapsed by the operator when desired.

In one form of last now in extensive use, the fore part and heel part are attached to each other by a link attached to the fore part and heel part by pins so located relatively that a line drawn through their centers will fall above the axis on which the last parts move when the last is collapsed and below this point or axis when the last is extended.

40 In such a construction, the greater the distance the pins are below the axis of the last when the last is extended, or the greater the distance they are above the axis of the last when the last is collapsed, the more resistance the last will offer to collapse or ex-

tension, but this distance is limited inasmuch as the pins must be located in the last body itself, and in the case of wooden lasts the pins must be kept at an appreciable distance from the bottom or sole face owing 55 to the danger of splitting the last when the same is in use or when being moved from extended position to collapsed position or vice versa.

In the present construction I have provided an arrangement for attaching the two last parts to each other whereby an effect is obtained which is as efficient as the lowering of the pins in the above-outlined construction to the danger point, the resistance 60 to collapse or extension offered by my last being very materially increased, without, however, necessitating placing of any pins at a point where they are likely to cause the last to split.

It is one of the especial objects of my invention to provide a last in which the last parts are held together under tension and not simply held in expanded or collapsed position under tension.

It is a further object of my invention to hold the last parts together by means employing a lever, with the parts constantly under tension.

It is a still further object of my invention 80 to hold the parts of the last together under tension with the parts so arranged that the tension will assume its maximum when the parts are either in their fully expanded or fully collapsed position.

It is an additional object of my invention to provide the holding together of the parts under tension and to associate therewith a lever, the parts being so arranged that the tension will achieve its maximum at the 90 completely expanded or collapsed position of the last parts. It will be realized that the tension may be created by a variety of means which may be very compressible or expandible, and that the details of creating 95 this condition are not essential.

It is a further object of my invention to provide such mechanism to hold the parts of the last together under tension that it will not be necessary to have resilient links 100

or resilient anchor pins. Such means are eliminated and the same results are obtained.

It is a further object of my invention to provide the holding of such parts together under tension and the increasing of this tension at extreme positions together with means to lock the parts in extended position by such tension means to resist the pressure, tending to collapse the last imposed on the bottom of the toe member in constructing the shoe thereon, until such tension means is overcome by the operator breaking the last.

15 The accompanying drawing is a sectional view illustrating my invention.

Referring to the drawing, I provide a last comprising a heel part 1 and a toe part 2, divided by an arcuate cut 3. These two parts are attached to each other by a lever or link 4, one end of which is pivotally attached to the toe part of the last at 5. The other end of this link extends into the heel part of the last, where it is pivotally connected at 6 to the broadened end of a lever 7, the latter being pivotally attached to the last heel by a fulcrum pin 8. The pins 5 and 8 are disposed relatively so that a line drawn through their centers falls below the axis 30 of the last when the last is extended and above that point when the last is collapsed. The forward end of the lever 7 extends into the toe part of the last and a spring 10 is interposed between this end of the lever and the lever 4, this spring being under compression at all times.

With the last parts in the position shown in full lines in the drawing, it will be seen that the spring 10 tends to force the forward end of the lever 7 upwardly, and as a consequence the rear end of the link 4 is being forced downwardly, to thereby draw the two last parts together and hold them in extended position under tension.

45 It will be apparent also that when the last parts are in collapsed or dotted-line position, the action of the spring 10 will hold the last parts in that position under tension also.

In this embodiment of my invention I have provided a collapsible instep 11 attached to the end of the link 4 forward of the pivot 5 by a link 12. With the last in extended position, the instep 11 will be held in its extended position by the link 12. When the last parts are moved to collapsed position, the point of attachment of the link 12 to the link 4 is moved relatively to the last toe to thereby draw the instep down into collapsed position.

60 It will be apparent that I have provided a last structure wherein the last parts are held in extended position and in collapsed position under tension, thereby providing a structure which will successfully withstand accidental collapse or extension of the last

parts when the same are in use in the manufacture of shoes. It will be seen also that in my invention I provide a structure in which the force exerted on the last parts to hold the last in extended and in collapsed position is of some magnitude, my improved construction being such, however, that this increase in force is provided without weakening the last. In other words, more power is available for holding the last parts in adjusted position due to my improved structure than is possible in lasts as now manufactured.

70 It will be seen also that I have provided a last structure wherein the last parts are held in extended position and in collapsed position under greatest tension. In other words, the tension under which the last parts are held to each other when the last is extended or when the last is collapsed, as the case may be, is greater than the tension under which the last parts are held when in an intermediate position.

Having thus fully described my invention, what I claim as new and desire to secure by Letters Patent is:—

1. In a last of the divided type and comprising a toe part and a heel part, a collapsible instep for the toe part, a link pivotally attached to the toe part intermediate the ends of said link, the rear end of said link extending into the heel part, an instep link attached to the forward end of the first-mentioned link and to said instep section, a second link pivoted to the heel part of the last and pivotally attached to said first-mentioned link at a point remote from the point of attachment of the second link to the heel part of the last, and a spring interposed between the last-mentioned link and the first-mentioned link for actuating said links in a direction to shorten the distance between the points of attachment of said links to the last parts to maintain the last parts in extended position and in collapsed position under tension, said instep link maintaining the instep in extended position when the last is extended and drawing the instep into collapsed position when the last is collapsed.

110 2. In a last of the divided type and comprising a toe part and a heel part, a collapsible instep for the toe part, a link pivotally attached to the toe part intermediate the ends of said link, the rear end of said link extending into the heel part, an instep link attached to the forward end of the first-mentioned link and to said instep section, a second link pivoted to the heel part of the last and pivotally attached to said first-mentioned link at a point remote from the point of attachment of the second link to the heel part of the last, and a spring interposed between the free end of the last-mentioned link and the first-mentioned link at a

point intermediate its ends for actuating said links in a direction to shorten the distance between the points of attachment of said links to the last parts to maintain the last parts in extended position and in collapsed position under tension, said instep link maintaining the instep in extended po-

sition when the last is extended and drawing the instep into collapsed position when the last is collapsed.

10

In testimony whereof, I affix my signature.

CLINTON M. SEARL.
